SANITARY RECTAL FOUNTAIN

Merle O. Gentry, Rte. 1, Box 890, Ventura, Calif.
Filed Oct. 3, 1961, Ser. No. 142,628
5 Claims. (Cl. 4—7)

This invention relates to attachments to toilet bowls and more particularly to an improved sanitary rectal fountain for cleansing the rectal area after defecation.

In my United States Patent No. 2,995,759, there is described a sanitary rectal fountain in which water spray is confined to the precise area to be cleansed with the resulting advantage that a minimum of the buttock area of the user is splashed with water. This rectal fountain is also designed to be swung to a position in the toilet bowl to intercept normal flushing water when not in use so that upon flushing of the toilet, the device will be washed and thus kept in a relatively sanitary condition, all in an automatic manner.

The present invention has as its primary object the provision of a rectal fountain similar to that described and claimed in my foregoing mentioned United States patent but including certain features providing an improved structure and mode of operation.

More particularly, it is found desirable to operate the fountain structure at the time that the initial toilet water is being flushed so that the operating structure itself is in a raised position to be free of the initial surge of flushing water. This positioning of the fountain structure will prevent contamination by any foreign matter being flushed. On the other hand, the device is designed to be repositioned adjacent the rear wall of the toilet bowl so that it will be cleaned by the latter portions of the flushing water and by subsequent flushings of the toilet in the manner as originally described in the above U.S. patent.

In addition to the foregoing, the instant invention provides an improved water outlet means in the fountain structure itself which will aid in cleansing the cup-shaped member surrounding the anal opening. Essentially, the improvement resides in the provision of small openings in the pipe in addition to the main outlet opening to direct water against the inside surface and upper edge portions of the cup-shaped member. This action cleanses the member in addition to that realized by subsequent flushing water after the device has been repositioned adjacent the rear wall of the toilet bowl to insure that sanitary conditions exist.

Another consideration, when operating the structure defined in my above-mentioned patent, relates to certain plumbing code requirements which require that any overflow be at least six inches below any atmospheric breaker. The instant invention accordingly incorporates in its structure means for automatically limiting the level to which the fountain structure may be swung so as to insure adherence to plumbing code provisions.

A better understanding of the improved sanitary rectal fountain will be had by now referring to the accompanying drawings, in which:

FIGURE 1 is an enlarged fragmentary perspective view illustrating in solid and dotted lines the improved sanitary rectal fountain of this invention; and

FIGURE 2 is a fragmentary side view partly in cross section of the improved cup-shaped structure and outlet openings employed in the structure of FIGURE 1.

Referring first to FIGURE 1, there is shown a conventional toilet bowl 10 provided with a seat 11 and the conventional cover 12, the latter being shown in the up position. Also provided is a conventional flush tank 13.

The sanitary rectal fountain of the present invention includes a pipe 14 extending transversely across the rear

2

portion of the toilet bowl 10 and having a central portion thereof rotatably coupled to the rear portion as shown. This central portion includes a T-joint 15 from which a branch pipe 16 extends terminating in an outlet cup-shaped structure 17. The pipe 16 extends normally away from the central portion of the pipe 14 as shown and in a first position will depend downwardly adjacent the rear wall of the toilet bowl 10.

One end of the transverse pipe 14 terminates in a closed bent portion 18 defining a handle for enabling rotation of the central portion of the pipe 14 about its own axis. The other end of the pipe 14 connects to a flexible hose 19, in turn having its inlet end connected to a push button valve 20 leading from a source of water supply indicated by the small arrow. The flexible hose 19 can accommodate a ninety degree torsional twist upon rotation of the pipe 14 by an upward swinging movement of the handle 18.

The operation of the structure described thus far in FIGURE 1 is identical to that set forth in the above-mentioned prior Patent No. 2,995,759. Rotation of the handle 18 through an arc of approximately ninety degrees to the dotted line position will swing the cup-shaped structure 17 and branch pipe 16 to a position generally parallel to the plane of the upper peripheral edges of the toilet bowl 10. The cup-shaped member is then in position to surround the anal area of the user and cause water passing from the end of the pipe 16 to impinge upon the area and cleanse the same.

The first improved structure of the instant invention over that described in the aforementioned patent takes the form of a laterally extending member 21 rigidly secured to the pipe 14 and caused to rotate therewith. An actuating rod 22 in turn has one end coupled to the member 21 and at its other end coupled to the flush handle 23 for the flush tank 13. With this arrangement, it will be evident that rotation of the pipe 14 between the solid dotted line positions shown will automatically cause operation of the flush handle 23 through the medium of the rod 22 to flush the toilet. Therefore, the toilet will be flushed only when the branch pipe 16 and cup-shaped fountain structure 17 is moved to its second or dotted line position free of the initial surge of flush water. Contamination of the structure by the excrement in the flush water during initial flushing is thus avoided.

In addition to the foregoing, the rod 22 will serve to limit the degree of upward swinging of the branch pipe 16 and cup-shaped member 17. This upward swinging is limited to a level no higher than the plane of the upper peripheral edges of the toilet bowl 10 so that plumbing codes requiring that any atmospheric breaker be at least six inches above an overflow are fully met.

It is understood, of course, that when the cup-shaped structure 17 is in the dotted line position and the toilet is being flushed, the user simultaneously operates the push button valve 20 to cause water to pass through the pipe 14 and branch pipe 16 and thereby spray the surrounding anal area.

The foregoing cleansing operation will become clearer by referring to FIGURE 2 wherein it will be noted that the cup-shaped structure 17 includes surrounding walls 24 and an upper annular seating surface 25. The bottom portion of the walls 24 is open so that water may drain therefrom. The pipe 16, as shown, terminates in a main opening 26 directed upwardly, and includes a plurality of smaller openings 27 disposed to direct spray adjacent the inside surface portions of the walls 24 and the upper edges of the seating surface 25, thereby thoroughly cleansing these areas as the anal area is being sprayed.

The terminal portion of the flushing operation will also serve to cleanse the cup-shaped member and other por-

tions of the rectal fountain when the same is returned to the first or solid line position illustrated in FIGURE 1. A subsequent or second flushing operation, of course, will also serve to cleanse the device. As mentioned, the feature of automatically flushing the toilet upon positioning the device in its dotted line or operating position avoids possible contamination of the device by excrement floating in the water at the initial portion of the first flushing.

The improved sanitary rectal fountain thus provides an automatic means for insuring that the toilet is flushed at the proper time during use of the device as well as providing a limiting means to avoid the possibility of violating any plumbing code provisions in the use of the structure.

What is claimed is:

1. In a toilet structure including a toilet bowl, flush tank, and flush tank operating handle, a sanitary rectal fountain comprising, in combination: a fountain structure swingably mounted to the upper rear portion of said toilet bowl for movement from a first position adjacent the rear wall of said bowl to a second position substantially parallel to the plane of the upper peripheral edges of said bowl; and actuating means coupling said fountain structure to said flush tank operating handle, whereby swinging movement of said fountain structure from said first position to said second position operates said handle to flush said toilet bowl.

2. The subject matter of claim 1, in which said sanitary rectal fountain structure includes a pipe mounted to the rear of said toilet bowl for rotation about its own axis, one end of said pipe being connected to a source of fluid and the other end of said pipe terminating in a handle, the intermediate portion of said pipe including a branch pipe extending normally therefrom and terminating in water outlet openings, said actuating means including a laterally extending portion integrally formed on said pipe and a single rod member having one end coupled to the end of said laterally extending portion and its other end coupled to said handle, whereby rotation of said pipe will move said rod in a general axial direction to operate said handle.

3. The subject matter of claim 2, in which the extent of said laterally projecting portion is adjusted such that said rod limits the degree of rotation of said pipe whereby

positioning of said water outlet openings is limited to a point no higher than the plane defining the upper peripheral edges of said toilet bowl.

4. In a toilet structure including a toilet bowl, flush tank, and flush handle, a sanitary rectal fountain comprising, in combination: a pipe having an inlet end for attachment to a source of water, the other end of said pipe terminating in a handle; coupling means intermediate the ends of said pipe for rotatably securing the central portion of said pipe to the upper rear edge portion of said toilet bowl; a branch pipe extending normally from said central portion and terminating in outlet opening means; a cup-shaped member surrounding said opening means and having an upper annular seating surface for engaging the user's rectal area over 360 degrees to surround the anal opening, the bottom of said cup-shaped member being open to drain water after passing from said outlet opening means to impinge against said rectal area and upper inside surface portions of said seating surface and cup-shaped member to cleanse the same, said coupling means allowing said pipe to rotate about its own axis through substantially ninety degrees to swing said branch pipe and cup-shaped member from a first position adjacent the rear wall of said toilet bowl to a second position substantially parallel to the plane of the upper peripheral edges of said toilet bowl during use; valve means adjacent the inlet end of said pipe for starting and stopping water flow from said source through said pipe and branch pipe to said opening means; and actuating rod means coupling said pipe to said flush handle whereby rotation of said pipe from said first to said second position operates said flush handle so that said toilet bowl is flushed while said branch pipe and cup-shaped member are in said second position.

5. The subject matter of claim 4, in which said actuating rod prevents swinging of said branch pipe and cup-shaped member above said plane of the upper peripheral edges of said toilet bowl.
